Attorney

UNITED STATES PATENT OFFICE.

EVART E. SMART, OF MINERAL WELLS, TEXAS.

HEEL PROTECTOR.

Application filed July 5, 1928. Serial No. 290,588.

The present invention relates to an improvement in heel protectors and has for its principal object to provide a device for detachable association with the heel and rear portion of the driver's shoes that rest on the floor of the car while driving an automobile.

5 The invention is particularly adapted for the protection of the heels of ladies' shoes when driving a motor car so that the heels and 10 back portions of the shoes or slippers will not become marked and disfigured by reason of their contact with the floor and operative parts of the automobile.

15 One of the important objects of the present invention is to provide a heel protector of the above mentioned character that can be readily and easily clamped on the heel portion of the shoe and furthermore can be quickly detached therefrom whenever desired.

20 A further object is to provide a heel protector of the above mentioned character which is simple in construction, combination and arrangement of the various elements forming the invention as more fully hereinafter described and claimed, reference being had to the accompanying drawings forming part thereof, wherein like numerals refer to like parts throughout, and in which:

25 In the drawing:
30 Figure 1 is a side elevation showing by improved heel protector clamped on a lady's shoe,

Figure 2 is a vertical sectional view through the device,

35 Figure 3 is a bottom plan view of the heel protector, and

Figure 4 is a detail perspective view of the frame forming a salient part of the present invention.

40 In the drawing wherein for the purpose of illustration is shown a preferred embodiment of my invention, the numeral 1 designates generally my improved heel protector, the same comprising a frame 2. This frame includes the upper and lower substantially U-shaped spring metal clamps 3 and 4 respectively, the upper clamps being of such size as to snugly engage with the rear portion of the shoe while the lower clamp engages snugly 45 with the lower edge portion of the heel.

50 These spring clamps are secured together in proper spaced relation by means of the vertically disposed spring strips 5, the same being secured at their upper ends to the free ends of the U-shaped spring clamp ring while the lower end portion of these vertically dis-

posed strips 5 are secured to the free end of the arms of the lower U-shaped spring clamp 4.

55 As clearly shown in Figure 4, these spring strips are slightly curved in order to conform to the curvature of the sides of the counter or back portion of the shoe. As also observed more clearly from this particular figure, the lower extremities of the spring strips 5 are directed inwardly as at 6.

60 A fabric covering 7 is disposed over the lower U-shaped spring clamp 4 and adapted for disposition against the lower edge of the spring clamp 4 in the bottom faces of the inwardly directed extremities 6 is the rubber bottom 8 that is stitched to the fabric covering 7 as at 9 and as is clearly shown in Figure 3.

65 This rubber bottom is slit inwardly as at 75 10 at the central portion thereof whereby the strips 5 may be spread apart to facilitate the placing of the heel protector on the rear portion of the shoe and the heel of the shoe will rest on the fabric covered upper face of the 70 slit rubber bottom 8 as suggested in Figure 1.

75 The remaining portion of the frame 2 is covered with a suitable piece of fabric denoted by the reference character 11 so that none of the metallic parts of the frame will be uncovered thus preventing the parts from coming in actual contact with the shoe and marring or otherwise defacing the same.

80 The protector can be readily and easily snapped on to the back and heel of a shoe as 90 shown in Figure 1 to properly protect this part of the shoe when the back portion of the shoe is placed on the floor and the operative parts of the automobile when driving.

85 The spring clamp will properly hold the 95 protector on the shoe and furthermore a protector can be readily and easily removed whenever desired and when worn will not cause any discomfort to the wearer. The use of a rubber bottom unit of the character 100 shown and described enables the device to be used on shoes having heels of different shapes and sizes.

95 The simplicity of my device enables the same to be manufactured at a very low cost 105 and will at all times be positive and efficient in carrying out the purposes for which it is designed.

100 While I have shown the preferred embodiment, it is obvious that my invention is susceptible to various changes and modifications in construction without departing from the 110

spirit of the invention or the scope of the appended claims, and I accordingly claim all such forms of the device to which I am entitled.

5 Having thus described my invention, what I claim as new is:

1. A heel protector of the class described comprising a frame including upper and lower substantially U-shaped spring clamps 10 for clamping engagement with the counter and heel portion of a shoe respectively, vertical strips of spring metal connected at their upper ends to the free ends of the arms of the upper U-shaped clamp and at their lower 15 ends to the free ends of the arms of the lower U-shaped clamp, a covering for the frame, said frame being entirely enclosed within the covering, and a piece of a rubber covering the bottom of the frame and secured to the 20 covering, said piece of rubber being slit inwardly from the forward edge.

2. A heel protector of the class described comprising a frame including upper and lower substantially U-shaped spring clamps 25 for clamping engagement with the counter and heel portion of a shoe respectively, vertical strips of spring metal connected at their upper ends to the free ends of the arms of

the upper U-shaped clamp and at their lower ends to the free ends of the arms of the lower U-shaped clamp, a covering for the frame, said frame being entirely enclosed within the covering, a piece of a rubber covering the bottom of the frame and secured to the covering, said piece of rubber being slit inwardly from the forward edge, the lower ends of the vertical strips being directed inwardly for engagement across the upper face of the forward edge portion of the slit rubber bottom. 30 35 40

3. A heel protector of the class described comprising a frame including upper and lower substantially U-shaped spring clamps for clamping engagement with the counter and heel portion of a shoe respectively, vertical strips of spring metal connected at their upper ends to the free ends of the arms of the upper U-shaped clamp, said strips being connected adjacent their lower ends to the free ends of the arms of the lower U-shaped 45 50 clamp, the lower extremities of the strip being bent inwardly for engagement with the bottom of the heel, and a covering for the frame.

In testimony whereof I affix my signature.
EVART E. SMART.
